UNITED STATES PATENT OFFICE.

DENNIS J. CREEDEN, OF NEW YORK, N. Y.

DESIGN FOR A LAMP-SIGN.

47,532.

Specification for Design.

Patented July 6, 1915.

Application filed March 13, 1915. Serial No. 14,253. Term of patent 7 years.

To all whom it may concern:

Be it known that I, DENNIS J. CREEDEN, a citizen of the United States, residing at the city of New York, county of New York, State of New York, have invented a new, original, and ornamental Design for a Lamp-Sign, of which the following is a specification, reference being had to the accompanying drawing, forming a part thereof.

The figure is a side elevation view of a lamp sign showing my new design.

I claim:

The ornamental design for a lamp sign, as shown.

DENNIS J. CREEDEN.

Witnesses:

JNO. DOYLE,
CHAS. T. LAVERRE.
